UNITED STATES PATENT OFFICE.

RICHARD STANFORTH, OF ROCHESTER, NEW YORK, ASSIGNOR TO ART IN BUTTONS, INC., OF ROCHESTER, NEW YORK, A CORPORATION OF NEW YORK.

PRODUCTION OR MANUFACTURE OF DISKS, OR BLANKS FOR BUTTONS OR THE LIKE.

Application filed April 9, 1923, Serial No. 631,045. Renewed November 21, 1928.

The present invention relates to the production or manufacture of disks, or blanks for buttons, or the like, from irregularly shaped pieces of material, and an object of 5 the invention is to provide a method by which the necessity for accurate classification of the irregularly shaped material is eliminated. Another object of the invention is to secure from suitable irregularly 10 shaped material the desirable maximum yield in disks, or blanks for buttons, or the like. Still another object of the invention is to convert the irregularly shaped material into blanks having regular and substantially 15 cylindrical characteristics and cut perimeters and article surfaces on opposite sides thereof, and thereafter to recut those blanks which have incomplete perimeters or incomplete article surfaces to provide 20 complete blanks of smaller diameter or thickness, or both, thus eliminating defectives. Still another object of the invention is to recut the incomplete blanks in accordance with predetermined graduated scales 25 covering a series of steps either or both of decreasing thickness and of proportioned finished surface curvatures, in order to make such recutting economically possible. Another and still further object of the invention 30 is to recut the incomplete plural blanks in accordance with the hereinbefore mentioned predetermined graduated scales in such a manner that the disks, or blanks for buttons, or the like, are obtained from the 35 most desirable portions of the irregularly shaped material. Another and still further object of the invention is to provide a method through which the objects hereinbefore mentioned may be accomplished with 40 machinery and other equipment now used in factories or plants for making buttons.

To these and other ends, the invention consists of certain steps, and combinations of steps, in a method of producing disks, or 45 blanks for buttons, or the like, from irregularly shaped material, all of which will be hereinafter described and the novel features pointed out in the appended claims.

In the drawings:

50 Fig. 1 shows perspective views of three typical irregularly shaped nut pieces;

Fig. 2 shows a nut piece in cross section illustrating in dotted lines the manner in which a single blank of substantially maximum diameter may be formed therefrom;

Fig. 3 shows a nut piece in cross section, illustrating in dotted lines the manner in which a plural blank of substantially maximum thickness may be formed therefrom;

Fig. 4 is a perspective view of a single 60 blank with its perimeter incomplete;

Fig. 5 illustrates side views of three plural blanks incomplete in one or more of their article forming portions;

Fig. 6 illustrates a manner in which the 65 incomplete single blank shown in Fig. 4 may be recut to form a complete blank of smaller size;

Fig. 7 illustrates an optional manner of recutting incomplete single blanks to a 70 smaller size;

Fig. 8 illustrates a manner of recutting the incomplete plural blanks shown in Fig. 5 to provide complete plural blanks of a 75 smaller size;

Fig. 9 illustrates another manner of recutting the incomplete plural blanks shown in Fig. 5 to provide complete plural blanks of a smaller size;

Fig. 10 shows an enlarged single blank, 80 illustrating diagrammatically thereon the predetermined graduated scale followed in the manner of recutting incomplete blanks illustrated in Fig. 6;

Fig. 11 shows an enlarged single blank 85 illustrating diagrammatically thereon the predetermined graduated scale followed in the manner of recutting incomplete blanks illustrated in Fig. 7;

Fig. 12 shows an enlarged plural blank 90 illustrating diagrammatically thereon the predetermined graduated scale followed in the manner of recutting incomplete plural blanks illustrated in Fig. 8; and

Fig. 13 shows an enlarged plural blank 95 illustrating diagrammatically thereon the predetermined graduated scale followed in the manner of recutting incomplete plural blanks illustrated in Fig. 9.

Buttons are most generally produced from 100 irregularly shaped material, such as bone, shell, or the pieces cut from the so-called "ivory" nut. When nut pieces, such as illustrated at 1, 2 and 3, in Fig. 1, are used, these are, according to common American 105 practice, classified with more or less care as to diameter and, in many cases, also as to shape and then cut or turned to form, in most instances, single buttons of various shapes and thicknesses. The total thick- 110

ness of the nut pieces is usually controlled in the cutting of the nut, so that, in this respect, the nut pieces run fairly uniform in each class or kind of sawing, and, in most cases, are considerably thicker than the single buttons produced therefrom.

The classification of these irregularly shaped nut pieces at best has been inaccurate owing to the great variety of shapes existing therein and this has required, in most cases, that the button made from each class be cut to a diameter less than the diameter of the smallest piece in the class in order to insure, as far as possible, the production of full and completely formed buttons. As a consequence, many of the irregularly shaped pieces from which larger and plural blanks could be obtained have been thus cut in such a manner as to cause a great deal of waste, and, furthermore, the comparatively few plural blanks which have been obtained by this old method have contained a large proportion of defectives which has represented a substantial loss.

According to this invention, the irregularly shaped pieces, such as 1, 2 and 3, whether obtained from nuts, or other sources, are preferably submitted to a rough mechanical classification for size, and the pieces of the different classes are then cut preferably on machines now in common use in button factories to obtain disks, or blanks for buttons, or the like, such as illustrated in incomplete forms at 4, 5 and 6 in Fig. 5, which are the desirable maximum in size for each class of the irregularly shaped pieces. In cutting these disks, or blanks, it is preferred to give them regular and cylindrical characteristics and to cut on opposite sides thereof article surfaces 7 and perimeters 8, the distance between such article surfaces preferably being sufficient to yield two or more single buttons, when such blanks are divided transversely. When using irregularly shaped material such as the nut pieces illustrated in the drawings, the diameter of the blanks obtainable therefrom is dependent upon the thickness of such blanks and vice versa, so that if buttons, or other articles of maximum diameter are desired, these may be obtained by cutting each irregularly shaped piece to yield a single disk, or blank, of minimum thickness, as shown at 9 in Fig. 2, whereas, if the largest number of buttons, or buttons of maximum thickness are desired, these may be obtained by cutting the blanks in the first instance to the maximum thickness for the irregularly shaped pieces, as shown at 10 in Fig. 3, with the diameters of the blanks decreased correspondingly. The expression "desirable maximum" as used in connection with yield in disks, or blanks for buttons, or the like, from the irregularly shaped pieces means yield of maximum value which is governed

by trade or market conditions and may be either of the extremes mentioned hereinbefore or any demand in between these extremes.

Owing to the fact that, in this new method, the irregularly shaped pieces are cut to produce blanks of the desirable maximum size obtainable therefrom, such blanks are not always full and complete in all portions thereof in the first instance, as will be apparent by reference to Figs. 4 and 5. Therefore, following the first cutting operation, the blanks are classified to separate those with incomplete perimeters 8 and incomplete article surfaces 7 from the blanks which are complete in both of these particulars and those of the latter blanks which contain a plurality of single disks, or blanks, are divided to obtain such single disks, or blanks.

The blanks with incomplete perimeters, or incomplete article surfaces are recut preferably according to predetermined graduated scales, examples of which are shown in Figs. 10 to 13, inclusive, covering a series either or both of decreasing thickness and of proportioned finished surface curvatures, to provide complete blanks of smaller diameter or thickness, or both.

One scale which may be employed and illustrated in Fig. 10, may be utilized for producing either single blanks, such as shown at 11 in Fig. 6, or plural blanks, such as shown at 12, 13 and 14 in Fig. 8. In producing the single blanks, such as shown at 11 in Fig. 6, each blank, after every cutting operation, is of uniform diameter from one face to the other and the center plane of the finished blank is not shifted with reference to the center plane α of the original incomplete blank. In Fig. 12, is shown a scale for cutting plural incomplete blanks, such as illustrated in Fig. 8. According to this scale the finished or complete plural blank will, in many instances, have two article forming portions of different diameters, as illustrated at 16 and 17 in Fig. 8, due to the fact that in recutting the incomplete plural blank only that portion which is incomplete is subjected to the recutting operation, but in this case also the center plane α of the blank is not shifted in the final recut blank.

Another scale which may be employed for producing single blanks is illustrated in Fig. 11, this being preferred when it is desired to obtain from an incomplete blank 15, a complete blank 18 located in the closest proximity to a superior side of the incomplete blank 15. According to this scale, the incomplete blank 15 is reduced in diameter and thickness, but the greater amount of material is removed from that side of the incomplete blank opposite the superior side, the latter being cut just sufficiently to change

the curvature to correspond to the reduced diameter, thus causing the shifting of the center plane y of the blank. A modified form of this same scale as illustrated in Fig. 5 13 may be utilized for producing plural blanks in the manner illustrated at 19, 20 and 21 in Fig. 9, the only difference between the results of using the two scales being that the different single blanks contained 10 in a plural blank will in many instances be of different diameters, due to the fact that incomplete plural blanks will only be cut in the article forming portion which is incomplete. As a consequence of this the 15 center plane y of the original incomplete blank is shifted as the different portions are reduced in diameter or diameter and thickness, for, it will be noted, that according to the scale used in Fig. 13 the superior portion 22 is reduced in diameter only, whereas the portion 23 away from the superior portion is reduced both in diameter and thickness.

The distances between the different divisions of the scales are variable with trade conditions. The curvature and thickness measurement bears, in this case, a definite relation to the diameter measurement to which it is preferred to adhere particularly 25 in the production of plural blanks, as it has been found by actual practice that the most economical results are thus to be secured. It will thus be seen that the irregularly shaped pieces are converted into blanks 30 having substantially regular and cylindrical characteristics, each blank still retaining for a predetermined thickness the maximum cylindrical diameter of the original irregularly shaped piece.

40 After the first recutting operation, the blanks are again classified to separate those which are complete from those incomplete and the latter are recut a second time to a smaller size in accordance with predetermined scales such as hereinbefore referred to. This method of separation and recutting is continued until all of the blanks have complete perimeters and complete finished article surfaces thereon, the complete plural 45 blanks produced by each recutting operation being divided to obtain single disks, or blanks. In many cases, it is possible, in the first instance, to determine that an incomplete blank will not yield a complete blank 50 of the next smaller size on the scale and in such cases the incomplete blank is recut directly to obtain a blank of two or more sizes smaller than the original.

55 It will thus be seen that after the first blank is produced, if incomplete, the recutting operations, according to the predetermined scale, will give finally a blank having complete and finished perimeters and complete and finished article surfaces on 60 opposite sides thereof, each blank still re-

taining for a predetermined thickness the maximum cylindrical diameter of the original irregularly shaped piece.

The inner finished surfaces or any or all of the single blanks obtained from each 70 plural blank may be provided simultaneously with the division of the plural blank, or in separate operations, as desired.

What I claim as my invention and desire to secure by Letters Patent is:

75 1. A method of producing disks, or blanks for buttons, or the like, from irregularly shaped pieces of material, which consists in roughly classifying the irregularly shaped pieces for size, severing from such 80 irregularly shaped pieces blanks having substantially regular and cylindrical characteristics, each blank still retaining the maximum cylindrical diameter for a predetermined thickness of the original irregularly 85 shaped piece, and cutting on each blank during such severing surfaces on its perimeter and on opposite sides thereof.

90 2. A method of producing disks, or blanks for buttons, or the like from irregularly shaped pieces of material, which consists in roughly classifying the irregularly shaped pieces for size, severing from such 95 irregularly shaped pieces blanks having complete and finished perimeters and complete and finished article surfaces on opposite sides thereof, each blank still retaining for a predetermined thickness the maximum cylindrical diameter of the original 100 irregularly shaped piece.

105 3. A method of producing disks, or blanks for buttons, or the like, from irregularly shaped pieces of material, which consists in cutting from the irregularly shaped pieces 110 blanks of circular form with finished button perimeters and at least one finished button face thereon, separating the blanks incomplete in any portion thereof from those complete in all portions, and recutting those blanks which have incomplete portions according to predetermined graduated scales 115 until the blank is complete in all portions and during each recutting providing on the blank a finished button perimeter and a finished button face.

120 4. A method of producing disks, or blanks for buttons, or the like, from irregularly shaped pieces of material, which consists in roughly classifying the irregularly shaped pieces for size, severing from such 125 irregularly shaped pieces blanks having substantially regular and cylindrical characteristics, each blank still retaining for a predetermined thickness the maximum cylindrical diameter of the irregularly shaped piece, cutting on each blank during such severing surfaces on its perimeter and on opposite sides thereof separating the blanks incomplete in any portion thereof from those 130 complete in all portions and recutting each

severed blank according to a predetermined graduated scale until a blank complete in all portions is obtained, still retaining for a predetermined thickness the maximum cylindrical diameter of the original irregularly shaped piece.

5. A method of producing disks, or blanks for buttons, or the like, from irregularly shaped pieces of material, which consists in cutting from the irregularly shaped pieces blanks having substantially regular and cylindrical characteristics, at the same time, cutting on each blank a finished button edge and at least one finished button face, recutting according to predetermined graduated scales covering a series of steps of decreasing thickness and of proportioned finished button face curvatures, those blanks which have incomplete button edges or incomplete finished button faces to provide complete blanks of a smaller size.
6. A method of producing disks, or blanks for buttons, or the like, from irregularly shaped pieces of material, which consists in severing from the irregularly shaped pieces plural blanks with perimeters and surfaces

on opposite sides thereof, separating the blanks with incomplete portions from those complete in all portions, and recutting by a succession of cutting operations according to a predetermined graduated scale the incomplete portion of each blank when adjacent one side thereof to a smaller diameter only and when adjacent the opposite side to a smaller diameter and thickness.

7. A method of producing disks, or blanks for buttons, or the like, from irregularly shaped pieces of material, which consists in severing from such material plural blanks having substantially regular and cylindrical characteristics, providing during such severing perimeters and convex article forming surfaces on opposite sides thereof, separating the blanks incomplete in any portion thereof from the blanks complete in all portions, and recutting an incomplete portion which is to form a single button without recutting the other portions forming the other buttons, so as to provide a complete portion of smaller size.

RICHARD STANFORTH.
